US00D781701S

(12) **United States Design Patent** (10) **Patent No.:** **US D781,701 S**
Brody et al. (45) **Date of Patent:** **** Mar. 21, 2017**

(54) **PACKAGE**

(71) Applicant: **Samsung Electronics Co., Ltd.**, Suwon-si, Gyeonggi-do (KR)

(72) Inventors: **Neville Stanley Brody**, London (GB); **Pyung-Hwa Lee**, Seoul (KR); **Seok-Young Kang**, Suwon-si (KR); **Nu-Ri Choi**, Suwon-Si (KR)

(73) Assignee: **S-PRINTING SOLUTION CO., LTD.**, Gyeonggi-Do (KR)

(**) Term: **15 Years**

(21) Appl. No.: **29/555,878**

(22) Filed: **Feb. 25, 2016**

(30) **Foreign Application Priority Data**

Aug. 28, 2015 (KR) 30-2015-0043603

(51) **LOC (10) Cl.** **09-03**

(52) **U.S. Cl.**

USPC **D9/432; D9/600**

(58) **Field of Classification Search**

USPC D9/414-434, 442-445, 456, 457, 542, D9/563, 600, 614-624, 655, 657, 658, D9/661, 695, 697-699, 707, 708, 711, D9/759, 772-776; D3/273, 276, 304, D3/310-313; D7/601, 602

CPC B65D 5/00; B65D 5/001; B65D 5/0015; B65D 5/1209; B65D 5/0227-5/0254; B65D 5/18

(57) **CLAIM**

The ornamental design for a package, as shown and described.

DESCRIPTION

FIG. 1 is a top, front, left perspective view of a package, showing our new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof; and,

FIG. 7 is a bottom plan view thereof.

The solid black and grey surface shading as shown in the figures represent contrast in appearances.
